Specification of Letters Patent. Patented Apr. 9, 1918.

Application filed December 15, 1914. Serial No. 377,375.

To all whom it may concern:

Be it known that we, HENRY G. VOIGHT and GEORGE B. PICKOP, citizens of the United States, residing, respectively, in New 5 Britain, Hartford county, and New Haven, New Haven county, Connecticut, have invented certain new and useful Improvements in Locks, of which the following is a full, clear, and exact description.

10 This invention relates to locks, and more particularly to corridor door locks of hotels and similar buildings, although the invention is applicable to locks of other types.

For hotel use a lock is required which can 15 be opened at all times, and under all circumstances, by means of a special key known as an emergency key, which is usually kept in the possession of the proprietor or manager. Moreover, in addition to the ordinary guest 20 keys, or change keys, the locks of a hotel, or like building, may usually be operated by a master (maid's) key, a grandmaster key, and sometimes by a display key, the functions of which are well understood in the 25 art. Usually all of these various keys act on a single group of tumblers, *e. g.*, a series of pivoted tumblers, or a series of pin tumblers in a cylinder lock, and therefore the lock structure is more and more complicated 30 as the number of functions of the lock is increased, and at the same time the security factor is decreased very considerably by the large number of tumbler changes required.

One of the primary objects of the present 35 invention is to provide a lock in which these disadvantages are avoided, and wherein an emergency key, or other master key, for controlling the door, is adapted to coöperate with a lock of very simple form. It is also 40 intended to provide a lock construction in which an emergency key adapted to open the door, under all circumstances, can coöperate with lock mechanism so constructed and arranged as to maintain the factor of security 45 at the maximum. The emergency key acts solely on its own special group of tumblers, whereby great security is obtained, and yet the improved lock is altogether devoid of complication, and may be inexpensively produced owing to the simplicity of its construction.

Another object of the invention is to pro-

vide a master key attachment which is readily and successfully applicable to existing locks. This can be done irrespective of 55 whether or not the locks as originally constructed are of the master keyed type. By our improvements, an additional key control can be provided, even without the necessity of removing such existing locks from 60 the doors to which they are applied.

We also contemplate the provision of means associated with, and carried by, the frame or casing of the door, and coöperating with a lock on the door, for controlling 65 the door by means of a key of any appropriate kind, which differs, however, from the key for operating said lock. It is also aimed to provide a lock-controlled strike applicable to the casing or frame of a door, 70 for the purpose of coöoperating with a door lock of any type whatever, and permitting the door to be opened by anyone having the key for the lock controlling the strike; and to improve generally, and in detail, the construction and operation of devices of the 75 class to which our invention relates.

To these and other ends, the invention consists in the novel features and combinations of parts to be hereinafter described 80 and claimed.

In the accompanying drawings,

Figure 1 is a fragmentary outside elevation of a door and casing equipped with our improvements,

85

Fig. 2 is a section on the irregular section line 2-2 of Fig. 1, showing the door locked,

Fig. 3 is a view similar to Fig. 2, with certain parts omitted, showing the door released by the key for the emergency lock associated with the frame or casing of the door,

Fig. 4 is a fragmentary view of the door casing, looking toward the face of the strike,

Fig. 5 is a fragmentary view, looking 95 from the outside of the room, with the casing member omitted, showing how the emergency lock is mounted,

Fig. 6 is a similar view with the cap plate of the emergency lock removed, the interior 100 parts of said lock being shown in door-locking position,

Fig. 7 is a view similar to Fig. 6, showing the door-releasing position,

Fig. 8 is a fragmentary view at right angles to Fig. 5, showing how the supporting bracket for the emergency lock is applied to the studding of the door frame.

5 Fig. 9 is a detail of the movable member of the strike, controlled by the auxiliary, or emergency lock, and

Fig. 10 comprises views of the change key and emergency key respectively.

10 In the particular embodiment of our invention which we have selected for illustration, the door is provided with an ordinary lock of the latch bolt type, having a fixed outer knob, and in which the latch bolt is adapted to be retracted from the outside by one or more keys of a suitable pin tumbler mechanism. The casing or frame of the door is provided with a strike plate having a part which may be moved to release the latch bolt, by the actuation of an appropriate key called an emergency key that operates an auxiliary or emergency lock associated with the door frame, and controlling the movable part of the strike. It will thus be seen that 25 when the door is locked, the possessor of the emergency key may readily open it by drawing back the movable strike member out of co-operation with the latch bolt, so as to gain access to the room in case of emergency or accident; and that when the movable part of the strike is again returned to its normal locking position, the lock on the door will act in the usual way. All of the features spoken of above are not essential parts of our invention in all its aspects, but they are mentioned to facilitate an understanding of the following description of the particular construction illustrated.

Referring to the drawings, A denotes the door, B the door frame or casing, C the lock on the door, D the strike on the casing, E the auxiliary or emergency lock associated with the casing, and F the movable part of the strike D, controlled by said auxiliary or emergency lock. The lock C is illustrated as of the mortise type, but this is unessential. It has a latch bolt 20 adapted to be retracted by one or more keys fitted to a pin tumbler cylinder lock 21, located in the usual manner on the outer face of the door. In the particular form shown, the lock C is provided with the usual live inside knob 22 for retracting the bolt, and the knob 23 at the outside of the door is a fixed or dummy knob, the retraction of the bolt from the outside being confined to the cylinder lock mechanism; but obviously, the outer knob 23 might be a latch-retracting knob adapted to be dogged by the usual movable stop work.

60 Located in a suitable notch 24 in the stud 25 of the door frame is a U-shaped bracket 26 secured to the stud by means of screws 27^a. This bracket 26 forms a support or carrier for the auxiliary lock E, which is fitted within 65 the intermediate part of the bracket, as

shown in Figs. 5 and 8, and suitably secured to the bracket in such a position as to lie wholly within the notch or other cutaway part in the stud. At its lower part, the bracket is provided with an extension 27 70 which may extend completely across the notch in the stud, as shown in Figs. 2 and 3, and which serves as a carrier for the movable member F of the strike. Preferably, the member F is of the pivoted type, being 75 pivoted or swiveled to the extension 27 by means of the pivot pin 28 at a point below the auxiliary lock E. The lock E is provided with a bolt 29, which carries a depending pin 30 extending out of the lock case, through a slot 31 in the bottom thereof, and engaging an opening or socket 32 in the movable strike member. Thus said movable strike member, being pivoted to the bracket at 28, and being operatively connected with the bolt 29, will 80 assume a locking position with respect to the latch bolt 20, when the bolt 29 is in the position shown in Fig. 6, and a releasing position in respect to said latch bolt when the bolt 29 is in the position shown in Fig. 7. 90 In other words, the bolt 29 of the auxiliary lock is adapted to hold the member F in locking relation to the latch bolt, but when said bolt 29 is moved back by its key 33, termed the emergency key, the movable strike 95 member F will be withdrawn from the locking position shown in Fig. 2 to the unlocking position shown in Fig. 3, so that the door may be opened from the outside merely by pushing on the same.

100 The auxiliary lock E, as previously stated, is located within the notch in the stud, so that when the covering or casing members of the door frame are applied, it will be securely housed in the interior of the casing. In some cases, however, the emergency lock might be applied to the exterior of the casing. The outer casing member is shown at 34, the inner casing member at 35, and the intermediate casing member 105 at 36, said last-named casing member being provided with the usual stop bead 37. Preferably, the upper and lower ends of the U-shaped bracket 26 will be mortised in the outer face of the stud and secured thereto, 110 by screws 27^a, so that the outer casing member may then be applied in the usual manner. The strike D is for the most part of customary form except that it is cut away at its inner edge to provide a space in which 115 operates a catch portion or lip of the movable member F, and said strike plate is mortised in the member 36 in the customary way. The movable strike member F may be advantageously of the form shown in Fig. 125 9, having a flat shank 38 adapted to lie, and be guided, on the plate 27, and having an upwardly extending lip or catch portion 39 to contact with the latch. Between the lip or catch portion and the pivoted extremity 130

of the strike member is a flat part 40, adapted to be positioned back of the opening in the fixed part of the strike, as shown in Fig. 2.

- 5 A keyhole 41 for the auxiliary lock E passes through the outside casing member 34, and preferably a small escutcheon 42 will be applied to said casing member around the keyhole. When the emergency
 10 key 33 is introduced into the lock E, and turned in the proper direction, it releases a plurality of tumblers 43 from engagement with the stump or fence 44 on the bolt 29, and retracts said bolt, thereby withdrawing
 15 the movable part of the strike. The bolt 29 is normally held in its forward position, corresponding to the locking position of the strike member F, by means of a spring 45. As the bolt 29 is retracted, the stump or
 20 fence 44 passes into notches 46 of the tumbler gatings, and immediately upon the release of the key 33 the bolt 29 will spring forward to its initial position, thereby returning the member F to the operative or
 25 locking position. The emergency key 33 is preferably of the drill pin type, as shown, and the key bit is prevented from making a full rotation in the keyhole by abutting a shoulder 47 on the bolt, so that the key
 30 cannot be turned to a position in which the bolt 29 is jammed back in position to release the movable strike member. In other words, the movable strike member cannot be held back without holding on to the key controlling
 35 the same.

In Fig. 10, we have shown a key 48 adapted to the cylinder lock 21, and intended for use as a change key or guest key. This particular key is, of course, of an absolutely
 40 different type from the emergency key 33, but in accordance with the broad principles of our invention, the difference of type is not important so long as each key retains its own particular function. We have not
 45 shown an additional key or keys for the lock on the door, such for example, as a maid's master key, but such additional key or keys may obviously be provided if desired.

The operation of the improved lock mechanism above described will be obvious for the most part from the foregoing description. Under normal conditions, the strike acts in the customary manner, that is to say, exactly like an ordinary strike, the lip of
 50 the movable member F being held and deadlocked in position to catch the head of the latch bolt. Obviously, the movable strike member cannot be shifted out of coöperation with the latch bolt when the bolt member
 55 29 of the emergency lock E is deadlocked (by means of the fence 44 and tumblers 43) in the advanced position shown in Fig. 6. Supposing, now, that the door of the hotel room is locked, with the guest inside, and
 60 65 the proprietor needs to gain access to the

room, as in case of accident or emergency, he can immediately open the door by means of the emergency key 33, even if the latch bolt has been deadlocked from the inside of the room (e. g., by a thumb turn 22^a) in 70 such a manner as to make the change key, and other keys, inoperative on the latch bolt from the outside. By simply inserting the emergency key in the keyhole in the casing, and giving it a slight turn, the strike is rendered inoperative to hold the latch bolt, and the door can be opened at once by merely pushing on the same. On releasing the hold on the emergency key, the spring 45, acting on the bolt 29, will immediately carry the 80 strike member F back to its initial position, so that when the door is again closed, the latch bolt will take into the strike in the usual manner, thus locking the door again.

It will be understood that by our invention, both the lock on the door and the lock in or on the casing, or door frame, can be made in the simplest form. Thus, in most cases, the two locks can be produced at a cost not appreciably greater than the cost 90 of a single lock providing all their combined functions. The security factor is very largely increased by our system, because the emergency key has its own group of tumblers to which it can be specially adapted, in order 95 to avoid all liability of picking the emergency lock, and because the simplicity of the lock on the door and the relatively small number of keys adapted to said lock, tend to security and safety. Complications in the 100 working of the lock mechanism are also avoided, owing to the simplicity of the construction. Furthermore, it is much easier to differentiate between the keys, so that no key will operate a lock which it is not intended to operate. The application of the 105 emergency lock to the casing or frame of the door can be very readily effected in the manner previously described, and the emergency lock can be applied to doors already 110 in use, by removing the casing members of the door frame, and mounting the lock in the studding, with the movable strike member in proper relation to the bolt on the door, after which the casing members can 115 be replaced. By this means, an ordinary lock which is not of the master-keyed type can be very readily converted into a master keyed lock. Again, even in the case of locks having one or more master keys, it is obvious 120 that by applying our emergency key attachment, an additional control of the lock and door is provided. Furthermore, by dividing the controls of the door between the lock on the door and the lock on the door frame, 125 it is possible to obtain a master-keyed system involving more controls than have ever been provided heretofore, in so far as we are aware. No matter how great the number of controls, the security of the lock mechanism 130

is obviously very much greater than in the case of the ordinary master keyed lock, and the mechanism is simpler and easier to manufacture.

5. We do not limit ourselves in all aspects of the invention to an arrangement in which the lock on the door is of the latch bolt type, nor to a construction in which the emergency, auxiliary, or controlling lock is 10 mounted on the door frame in the particular manner herein described. Furthermore, we do not limit ourselves to a construction in which the strike is provided with a movable catch member, inasmuch as the means for 15 operating the bolt on the door, by means of the auxiliary, or emergency lock, may be considerably varied. Neither do we limit ourselves to a lock mechanism in which a movable strike member automatically 20 returns into coöperative position with respect to the door bolt, when the emergency key is released. Again, we do not intend to limit ourselves to a mechanism in which the control of the door, gained by providing the 25 auxiliary, or emergency lock, is limited to the function of opening the door by means of a so-called emergency key. Moreover, the lock on the door need not be operable by a key in some cases. Various changes in these 30 and other respects may be adopted within the scope of our invention as defined in the claims.

What we claim is:

1. The combination with a door and door frame, of a bolt on the door, a catch member for said bolt mounted on the door frame, and a key to move said catch member into a position to release the door; substantially as described.

40 2. The combination with a door and door frame, of a bolt on the door, a catch member for the bolt mounted on the door frame, a key for moving said catch member into a position to release the bolt, and means for 45 returning said catch member to its normal position; substantially as described.

3. The combination with a door and door frame, of a bolt on the door, a bolt on the door frame, a key for actuating said last-named bolt, and a door-releasing member 50 movable with said second bolt to door-releasing position; substantially as described.

4. The combination with a door and door frame, of a bolt on the door, a bolt on the door frame, a movable door-releasing member adapted to be shifted to door-releasing position by said second bolt, and means for returning said member and said second bolt to their initial positions; substantially as 55 described.

60 5. The combination with a door and door frame, of a bolt on the door, a pivoted keeper member on the door frame to coöperate with said bolt, a bolt on the door frame for moving said keeper member to an inoper-

ative position, and a key for actuating said second bolt and said keeper member; substantially as described.

6. The combination with a door and door frame, said door frame having a hollow portion therein, of a lock mechanism on the door, a change key for operating said lock mechanism in order to release the door from the door frame, an emergency key insertible into said hollow portion of the door frame, 75 and means in said hollow portion of the door frame, coöperating with said emergency key and with the lock on the door; substantially as described.

7. The combination with a door frame 80 having a stud with a notch therein, of a lock mounted in said notch, casing members enclosing said lock, means for actuating said lock, and a door-controlling member operative by said lock; substantially as described. 85

8. The combination with a door and door frame, of a bolt on the door, a movable member mounted on the door frame to release the door from the frame, and a key to move said member in either of two directions; substantially as described.

9. The combination with a door and door frame, of a bolt on the door adapted to lock the door to the frame, a movable door-releasing member mounted on the frame, a sliding member on the frame for moving said door-releasing member in either of two directions, and a key for actuating said sliding member; substantially as described.

10. The combination with a door and door frame, of a lock on the door having a bolt, a strike on the door frame having a movable part to coöperate with said bolt, an auxiliary lock connected with said movable strike member to operate the same, and a key for 100 actuating said auxiliary lock; substantially as described.

11. The combination with a door and door frame, of a lock on the door for locking the latter to the frame, a key for operating said 105 lock from the outside of the door, means for preventing operation of said lock by said key, a second key, and means on the door frame operable by said second key for releasing the door from the frame when said preventing means is in operative condition; substantially as described.

12. The combination with a door and door frame, of a latch on the door, a key for withdrawing said latch from the outside of 110 the door, means for preventing the retraction of said latch by said key, a second key, and means on the door frame operable by said second key for releasing the door from the frame when said preventing means is 115 in operative condition; substantially as described.

13. The combination with a door and door frame, of a latch on the door for locking the latter to the frame, a key for retracting said 120

- latch from the outside of the door, means 5
operable from the inside of the door for preventing retraction of said latch by said key, a second key, and means housed in the door frame and operable by said second key for releasing the door from the frame irrespective of the condition of said preventing means; substantially as described.
14. The combination with a door and door frame, of a lock on the door for locking the latter to the frame, a movable keeper member on the frame coöperating with said lock, a change key for unlocking said lock from the outside of the door, means operable from 10
the inside of the door for preventing the unlocking of said lock by means of said change key, an emergency key, and means operable by said emergency key for shifting said keeper member to door-releasing position; 15
substantially as described.
15. The combination with a door and door frame, of a lock on the door having a latch bolt, a strike on the door frame having a movable keeper member to coöperate with 20
said latch bolt, a change key for retracting said latch bolt from the outside of the door, means for preventing the retraction of said latch bolt by means of said change key, an emergency key, a tumbler-controlled member 25
on the door frame movable by said emergency key, and means of connection between said tumbler-controlled member and said movable keeper member; substantially as described.
- 30
35. 16. The combination with a door and door frame, of a bolt on the door frame, a key for operating said bolt, and a door-locking member movable into and out of operative position by said bolt; substantially as described.
- 40
45. 17. The combination with a door and door frame, of a bolt on the door frame, a plurality of tumblers for said bolt, a key for said bolt, and a door-locking member operatively connected with said bolt so that the former is moved into and out of operative position by the latter; substantially as described.
- 50
55. 18. An emergency attachment for locks adapted for application to a door frame, comprising a movable strike member, a lock connected with said strike member, to move the same, and having one or more tumblers, and a key for said lock; substantially as described.
- 60
65. 19. The combination with a door and door frame of a bolt on the door, a key for actuating said bolt, a movable strike member on the frame for coöperating with said bolt, a lock for actuating said movable strike member having one or more tumblers, and a second key different from the first, for operating said lock from the door frame; substantially as described.
20. The combination with a door having 65
a locking bolt, of a door frame having a notch therein, a lock mounted in said notch, casing members inclosing said lock, a key insertible into the casing to actuate said lock, and a door controlling member operative by said lock and coöperating with said locking bolt; substantially as described.
- 70
75. 21. The combination with a door having a locking bolt, of a door frame having a notch cut therein adjacent the door, a lock mounted in said notch and comprising a bolt and one or more tumblers, casing members applied to the frame and inclosing said lock, a key insertible through one of said casing members to actuate the bolt of the lock in said notch, and a door controlling member actuated by said last named bolt, and coöperating with the bolt on the door; substantially as described.
- 80
85. 22. The combination with a door and door frame, of a latch bolt on the door for locking the door to the frame, a movable catch member on the frame coöperating with said bolt, a lock for moving said catch member out of coöperation with said bolt, a key for said lock, and means for returning said catch member into coöperation with said bolt, when the key is released; substantially as described.
- 90
95. 23. An emergency attachment for locks, comprising a strike, a movable member coöperating with said strike, and a key bolt for actuating said movable member; substantially as described.
- 100
105. 24. An emergency attachment for locks, comprising a strike, a movable door-releasing member coöperating with said strike, and a key bolt operatively connected with said member to actuate the same; substantially as described.
- 110
115. 25. An emergency attachment for locks, comprising a strike, a movable door controlling member coöperating with said strike, a bolt for operating said member connected therewith, tumblers for said bolt, a case for said bolt and tumblers, means for mounting all of said parts on a door frame, and a key for said bolt; substantially as described.
- 120
125. 26. The combination with a door and door frame, of a bolt on the door frame, a key for operating said bolt, and a movable door-controlling member on the frame operative by said bolt; substantially as described.
- 130
135. 27. The combination with a door and door frame, of a bolt on the door for locking the door to the frame, a key bolt on the frame, and means operative by said key bolt for controlling the locking together of the door and frame by said first bolt; substantially as described.
28. The combination with a door and door frame, of a lock on the door for locking the latter to the frame, a change key for operating said lock from the outside of the door, means operable from the inside of the door for preventing the retraction of the bolt of

5 said lock by means of said change key, an emergency key, and means on the door frame operable by said emergency key for releasing the door from the frame when said preventing means is in operative condition; substantially as described.

29. In a lock structure for doors, a catch member for the lock bolt, mounted on the door frame, and yieldingly held in the door-locking position; and a key for moving said catch member into door-releasing position; substantially as described.

30. In a lock structure for doors, a catch member for the lock bolt, mounted on the door frame, a spring normally holding said catch member in door-locking position, and key actuated mechanism for moving said catch member into door-releasing position in opposition to said spring; substantially as described.

31. In a lock structure for doors, a catch

member for the lock bolt, mounted on the door frame, and key actuated means for shifting said catch member into inoperative position; substantially as described.

25

32. In a lock, a key for operating the lock from the outside of the door operating in a keyhole in the door, and a second key operating in a keyhole on the door frame when the first key is rendered inoperative from the inside of the room for releasing the door from the frame; substantially as described.

33. In witness whereof we have hereunto set our hands on the 12th day of December 1914.

HENRY G. VOIGHT.
GEORGE B. PICKOP.
